UNITED STATES PATENT OFFICE.

JOHN CREAGAN AND CHARLES D. TYLER, JR., OF CLEVELAND, OHIO.

SPRING-SETTER.

SPECIFICATION forming part of Letters Patent No. 258,382, dated May 23, 1882.

Application filed August 20, 1881. (No model.)

To all whom it may concern:

Be it known that we, JOHN CREAGAN and CHARLES D. TYLER, Jr., of Cleveland, Cuyahoga county, Ohio, have invented a new and 5 useful Improvement in Spring-Setters, of which the following is a specification, reference being had to the accompanying drawings, forming part thereof.

Figure 1, Sheet 1, is a plan view of our improvement, partly in section through the line *x x*, Fig. 2. Fig. 2, Sheet 1, is a sectional side elevation of the same, taken through the line *y y*, Fig. 1. Fig. 3, Sheet 2, is a sectional end elevation of the same, taken through the line *z z*, Fig. 1.

Similar letters of reference indicate corresponding parts.

The object of this invention is to facilitate the setting of springs and promote convenience 20 in adjusting the machine to give the desired form to the springs.

A represents the frame of the machine, to the end bars of which are attached the ends of two rods, *B*, which extend along the inner sides of 25 the side bars of the said frame to serve as supports and guides for the sliding plates *C D*. The plates *C D* have upwardly-projecting flanges upon their end edges and the end parts of their outer side edges to form beds for the adjustable 30 fingers or bars *E*. The plates *C D* have lugs upon their ends, in the outer ends of which are formed half-round notches or recesses to receive, fit, and slide upon the rods *B*. In the 35 faces of the plates *C D* are formed grooves to receive the bars *J*, which extend across the space between the said plates *C D* to receive and support the spring to be bent or set. Upon 40 each of the plates *C D* are laid a series of fingers or bars, *E*, placed side by side, and the ends of which project beyond the inner edges of the said plates *C D*. The fingers *E* are held 45 down upon the plates *C D* by the cross-bars *F*, which are placed upon the said fingers *E*, and their ends are secured to the end flanges of the plates *C D* by the screw-bolts *G*. The 50 fingers *E* are pressed together to further secure them in place by screws *H*, which pass through the end flanges of the plates *C D* and press against the side fingers, *E*. The fingers *E* can be conveniently released and adjusted to give any desired form to the springs by loosening the screws *G H*. The end parts of the outer

edge of the forward plate, *D*, rest against the end parts of a curved spring, *I*, the middle part of which rests against and may be secured to the forward cross-bar of the frame *A*, so that the plate *D* will not encounter a rigid resistance when subjected to pressure in setting a spring. The fingers *E* upon the two plates *C D* are so arranged that the inner ends of each 60 set of fingers will describe the curve to be given to the spring, as shown in Fig. 1.

To the under side of the middle part of the rear frame, *C*, is attached, or upon it is formed, a nut, *K*, the screw-thread of which fits into 65 the thread of the screw *L*, placed below the plates *C D* and swiveled in bearings attached to the frame *A*. The rear end of the screw *L* projects and revolves in bearings formed in or attached to the post *M*, which is strengthened 70 in a vertical position by a rod, *N*, attached to its upper part and to the upper part of a vertical frame, *O*, attached to the rear end of the frame *A*. Upon the projecting rear part of the screw *L* are placed two fast pulleys, *P*, and 75 two loose pulleys, *Q*, the said loose pulleys being placed side by side and between the two fast pulleys *P*. The forward pair of pulleys, *P Q*, is provided with a straight belt, *R*, and the rear pair of pulleys, *Q P*, is provided with 80 a crossed belt, *S*. The belts *R S* pass around a long pulley, *T*, attached to the shaft *U*, which revolves in bearings formed in or attached to the upper ends of the post *M* and frame *O*. The shaft *U* is designed to receive the driving- 85 power, which may be applied by means of a crank, a pulley and belt, or other suitable means.

V is a semi-cylindrical plate, which passes around the lower parts of the loose pulleys *Q*, 90 and has its end parts slotted transversely to receive the bolts *W*, that pass through longitudinal slots in the arms *X*, which project upward and have slots formed in their upper ends to receive the belts *R S*, so that both the belts 95 can be shifted at one movement of the belt-shipper, to bring both the belts upon the loose pulleys or to bring either of the belts upon a fast pulley, as may be required. The slots in the plate *V* and arms *X* allow the belt-shipper to be so adjusted that it will move the belts the distance required. The middle part of the curved plate *V* is rigidly secured to a bar, *Y*, the rear part of which slides in bearings 100

in the post M and in the short post Z, placed at a little distance from the post M and connected with it by a tie-rod, a. The forward end of the sliding bar Y is pivoted to the upper end of a bar, b, the lower end of which is pivoted to the upper end of a short standard, c, attached to the floor, the bed of the machine, or other suitable support.

To the lower end of the bar b is attached, or with it is rigidly connected, the inner ends of two arms, d e, which project, the one outward and the other inward, at right angles with the said bar b, making it a double angle-lever. With this construction, by moving the outer end of the arm d downward the straight belt will be shifted to the forward fast pulley P and the crossed belt to the loose pulley Q, and the screw L will be turned forward to set the spring. When the outer end of the arm e is moved downward the crossed belt will be shifted to the rearward fast pulley P and the straight belt to the loose pulley Q, and the screw will be turned back to release the spring. This construction allows separate treadles to be connected with the outer ends of the two arms d e, so that the belts can be shifted by foot-power.

To the sliding bar Y is attached an upwardly-projecting pin, f, which passes through a slot 30 in the inner end of the lever g. The lever g, at a little distance from its outer end, is pivoted to a standard, h, attached to the floor or other suitable support. To the end of the short arm of the lever g is pivoted the end of a rod, i, which slides in bearings in hangers j and k. The forward hanger, j, is attached to the frame A. The rear hanger, k, is attached to the rear plate, C, so as to be carried back and forth by the said plate in its movements upon the 40 guide-rods B.

To the rod i, upon the opposite sides of the hanger k, are attached collars l m, in such positions that when the plate C is carried forward by the movement of the screw L it will bring 45 the hanger k in contact with the forward col-

lar, m, and operate the belt-shifter to move the belts R S upon the loose pulleys. In the same manner, when the plate C is completing its rearward movement, the hanger k comes in contact with the rear collar, l, and shifts the 50 belts to the loose pulleys. The belts are moved from the loose pulleys to the fast pulleys to give motion to the screw L, to move the plate C in either direction by operating the double angle-lever b d e.

To the center finger, E, secured to the plate D, is attached, or upon it is formed, a point, n, to enter a hole in the center of the spring-blank, to center the said blank, and thus insure its receiving the proper shape.

Having thus fully described our invention, we claim as new and desire to secure by Letters Patent—

1. The combination of the rods B, the grooved end flanged plates, C D, having notched end 65 lugs, the adjustable bars E, held down by bars F, the bolts G, the screws H, and the bars J, as and for the purpose specified.

2. The combination, with the slide-bar Y, of the slotted lever g, the pivoted slide-rod i, provided with collars l m, and the hangers j k, one of which is attached to movable plate C, as and for the purpose specified.

3. The combination, with the frame C, of the nut K, the screw L, the two fast pulleys Q, 75 the straight belt R, the crossed belts S, the long pulley T on drive-shaft U, the slotted curved plate V, the slotted arms X, the pivoted slide-bar Y, and the bar b, pivoted to standard c and having arms d e, as and for the purpose specified.

4. In a spring-setter, the combination, with the sliding bar Y of the belt-shifter, of the double angle-lever b d e, substantially as herein shown and described.

JOHN CREAGAN.
